BRASSIÈRE

Clara B. Studler, Glendale, Calif.

Application July 30, 1951, Serial No. 239,267

3 Claims. (Cl. 2—42)

1

This invention relates to a garment having means for functioning as a brassière, and in the following specification, the invention is described as constructed simply as a brassière, but it should be understood that the features of the brassière about to be described may, if desired, be incorporated in any suitable garment or lingerie, such as a slip, for example.

The brassière about to be described is of a type characterized by the fact that the article functions without the use of any belt or girdle located at the waist line. In other words, the level of the brassière on the wearer's body is confined to the level of the breasts and a relatively limited distance below the horizontal plane in which the breasts lie.

One of the difficulties encountered in constructing a brassière of this type involves the location of the shoulder straps and their relation to each other, particularly at the back; and in this connection it should be stated that it is most desirable, if possible, to dispose the shoulder straps that support the brassière at the front in such a way that at the back the straps will not be seen when the wearer has donned a fairly low cut shirt waist or bodice.

Another difficulty experienced by women wearing brassières is that the shoulder straps often have a tendency to slide down off the shoulders, and this tendency, of course, becomes worse if the wearer is dancing.

Accordingly, a principal object of the present invention is to provide a brassière with features of construction that will co-operate to prevent the shoulder straps from slipping off the shoulders, or on the other hand from exhibiting a tendency to climb up on the wearer's neck.

Another object of the invention is to provide a brassière constructed so that it presents a bandeau worn across the breast, provided with a single location at which the ends of the bandeau can be connected to each other, and having an elastic connection at the back connected into the bandeau in such a way as to insure the presence of sufficient yielding tension in the shoulder straps to give comfort indirectly and at the same time holding the rear ends of the shoulder straps at a point in the bandeau that will give the straps a direction in passing over the shoulder tending to prevent their slipping down off the shoulders, or a tendency to climb up on the wearer's neck.

Another object of the present invention is to provide a brassière such as described with features of construction that will insure that the brassière will be comfortable when worn.

2

Further objects of the invention will become evident from a careful reading of the following specification, and a study of the accompanying drawing.

5 The invention consists in the combination of parts all of which contribute to produce an efficient brassière.

In the drawing:

Figure 1 is a perspective showing the forward 10 side only of a brassière embodying this invention, its relation to the wearer's body being indicated by dotted lines.

Figure 2 is a view similar to Figure 1 but showing the brassière as viewed from the rear, and in 15 a normal state.

Figure 3 is a fragmentary view illustrating the anchor point for the rear ends of the shoulder straps, and their adjacent parts; and indicating also the relation or action of the elastics 20 at the rear of the bandeau when an abnormal tension is developed in the shoulder straps.

Figure 4 is a rear fragmentary view similar to Figure 3 but illustrating a slight variation in the action of the rear anchor connection for the 25 straps particularly as affecting the degree of extension developed in the elastic by reason of a slight variation in the character of a pad which I employ between the elastics.

Figure 5 is a fragmentary view, and is a cross-section through the connection point of the bandeau taken about on the line 5—5 of Figure 1, and particularly illustrating how the fastening means is neatly covered and concealed at a point on the forward side of the bandeau.

35 Referring particularly to the drawing, in practicing the invention I provide a bandeau 1, which preferably has its greatest depth or width on the medial vertical plane between the two cups 2 that are carried by the bandeau.

40 The bandeau 1 is preferably in one piece with its detachable fastening means at the vertical line 3 where the forward edges of the sides of the bandeau overlap each other. The construction at this point is illustrated in detail in Figure 5 and is described more specifically hereinafter.

45 Each cup 2 is preferably composed of a lower section or portion 2a which has the usual central seam 6 to enable it to be given substantially the shape of a half cone, while the upper portion of each cup includes a portion 2b that is curved above, the lower edges of which are stitched to the side edges 7 of the lower portion 2a of the cup. In this way a peak 8 is formed on each cup.

50 At the base of the upper portions 2b an upward extension 9 is formed substantially in vertical

line with the peak 8, and at these points 9 the shoulder straps 10 are attached.

As shown clearly in Figures 1 and 2 the sides 1a of the bandeau taper in width from the relatively wide portion at the point 1c adjacent to the lateral side edges of the cup, to their rear edges 1b where the bandeau is relatively narrow.

The rear edges 1b of the bandeau are permanently secured together by a connection including a pad 11 located in line with the medial vertical plane, and the ends of this pad are connected by elastic strips 12 to the edges 1b. The details of this connection are illustrated clearly in Figures 3 and 4.

The pad 11 is preferably formed of a fabric of two or more layers, and to the middle portion of its upper edge 15 the rear ends 13 of the shoulder straps 10 are secured by sewing. They are preferably attached so that they form an angle 14 between them the vertex of which is located substantially at the upper edge of the pad.

The pad 11 is preferably of rectangular form.

In Figure 2 the pad 11 is disposed in a horizontal position so that it is in line with the edges 1b of the sides 1a of the brassière, and in this view the upper edge 15 of the pad is substantially horizontal. This is the normal position for the pad when the brassière has been properly adjusted to the wearer's body. However, if there is an increase of tension in the shoulder straps for any reason, this tension naturally operates to raise the pad 11 out of line with the edges 1d as indicated in Figure 3, so that the edge 15 will assume a slightly convexly curved condition, substantially as shown. This movement raises the end portions 16 of the pad 11 to an extent so that the elastics 12 become inclined and slightly stretched. In this way the tension exerted by the elastics becomes slightly increased, and by reason of the fact that the elastics become inclined somewhat, as shown in Figure 3, the vertical component of the inclined tension or pull meets this increased tension in the strap and tends to establish equilibrium again.

In Figure 4 I illustrate a slight modification in the character of the pad designated by the number 11a. This pad is relatively stiffer than the pad 11 and if desired this may be accomplished by starching and ironing a pad such as the pad 11, though other means may be employed, if desired, to give this pad increased stiffness as compared with the pad 11; and the effects are desirable because, due to the stiffness of the pad its ends 17 will be relatively elevated as compared with the ends of the pad 11. This gives relatively an increased upward inclination of the inner pad of the elastics 12, and due to the relatively increased inclination the vertical component of the inclined pull is relatively greater. In addition to this the relatively stiff pad imparts this vertical component force to the lower ends of the strap 10 more effectively.

The width of the bandeau is such that its forward face is wide enough to enable the entire lower edge 18 of each cup to be stitched to it, so that the lower edges of the cups are spaced a short distance above the lower edge 19 of the bandeau which is disposed in a substantially horizontal plane throughout its entire length.

Each shoulder strap is preferably provided with an adjustable connection 20 which in Figure 1 is illustrated as located at the front.

Referring to Figure 5, the connection at the dividing line 3 for the forward ends of the bandeau, preferably includes overlapping flaps 21 and 22 at the front side which conceal any fasteners such as hooks and eyes 23 which may be employed. On the inner side such a fastener should be covered by a relatively wide flap 24 which prevents the fastener from coming in direct contact with the surface of one's body. It should be understood, however, that any suitable fastening means such as zippers may be employed at this point, if desired.

Many other embodiments of this invention may be resorted to without departing from the spirit 15 of the invention.

I claim as my invention and desire to secure by Letters Patent:

1. A brassière comprising a bandeau having its greatest width at its front, substantially on the medial vertical plane of the brassière, a pair of cups carried by said bandeau located respectively on opposite sides of the said medial plane and having peaks respectively substantially in their medial plane, said bandeau being divided on its forward side so as to present two adjacent edges and having fastening means for connecting said edges, the sides of said bandeau terminating short of said medial plane at the back, and tapering in width from a relatively wide portion attached 25 to the outer lateral edges of said cups to a relatively narrow width at its rear edges, a pad disposed between said rear edges; elastic strips respectively connecting the ends of said pad to the said rear edges; and shoulder straps attached 30 adjacent to each other at their tips at their rear ends to the middle portion of said pad so as to form a single angle with each other, the vertex of which is located substantially at the upper side edge of said pad, to enable said straps to extend 35 free and unobstructed up over the shoulders and down at the front, and having their forward ends attached to the cups substantially in line with the peaks thereof.

2. A garment according to claim 1 in which the said pad is relatively stiff so as to cause its ends to become relatively elevated when tension is increased in the straps, thereby increasing the tension in the elastic strips.

3. A garment operating as a brassière according to claim 1, in which the said pad is substantially rectangular and composed of starched fabric of sufficient stiffness to cause the pad to substantially retain its rectangular form when tension in the straps is increased, thereby causing a relative increase in the degree of stretching imparted to the said elastic strips.

CLARA B. STUDLER.
